ATTI. 185.

UNITED STATES PATENT OFFICE.

REGINALD ARTHUR FEATHERSTONE-SMITH AND MEHERJIBHOY BOMANJI COOPER,
OF LONDON, ENGLAND.

PROJECTILE FOR DESTROYING AIRSHIPS, BALLOONS, AND OTHER AEROSTATS.

1,139,354.

Specification of Letters Patent.

Patented May 11, 1915.

Application filed September 19, 1914. Serial No. 862,501.

To all whom it may concern:

Be it known that we, REGINALD ARTHUR FEATHERSTONE-SMITH and MEHERJIBHOY BOMANJI COOPER, subjects of the King of Great Britain and Ireland, and residents of London, England, have invented certain new and useful Improvements in Projectiles for Destroying Airships, Balloons, and other Aerostats; and we do hereby declare the following to be a full, clear, and exact description of the same.

This invention relates to improvements in projectiles for destroying airships, balloons and other aerostats (hereinafter for convenience referred to as airships) having bags or envelops inflated with light gas such as hydrogen or hydrocarbon gas for keeping them afloat.

The present invention is characterized by constructing the projectile with one or more passages for gas from the airship gas bag and outside air or oxygen to pass along to form an explosive mixture in the bag or inner and outer envelops of the airship and in the projectile, by adapting the projectile with means for automatically igniting the explosive mixture to destroy the airship, by providing the projectile with means for forcing a blast of air into the gas bag of the airship to hasten the production of the explosive mixture, and by adapting the projectile with means for limiting its penetration into the gas bag of the airship, as hereinafter particularly described with reference to the accompanying diagrammatic drawings in which:

Figure 1 is a sectional elevation, showing the projectile piercing the outer and inner envelops of an airship; Figs. 2, 3, 4 and 5, are sectional plans on A—A, B—B, C—C, and D—D, Fig. 1. Figs. 6, 7, 8 and 9 are sectional elevations of modifications.

According to the construction represented, the projectile, 6, is constructed with an upward air passage, 7, and a downward gas passage, 8, separated by a partition, 9. The air passage, 7, opens, at 10, through the nose of the projectile and communicates with a blower, 11, driven for example by an electric motor, 40, connected by leads, 41, to a battery, 12, in the tail of the projectile; see Fig. 1. The blower draws in air through

openings, 13, in the tail, and is controlled by a switch, 14, which, before the gun or the like discharging instrument is loaded, is held open by a set screw or the like, 34, engaging a pin, 33, pivoted to the switch. When the gun is to be loaded the set screw is removed and the pin pressed in to insert the projectile. While in the gun, the switch is held open by the pin, 33, contacting with the bore of the gun. In lieu of the set screw, the pin may be held open by a cartridge case. The switch is closed when the projectile is discharged, by a spring, 35.

It will be obvious that in lieu of an electric motor to drive the blower, a clockwork motor, 42, may be used connected up by a suitable transmission, 43. The motor may be controlled by a pin, 44, engaging a ratchet wheel, 45, on the motor spindle. The pin is actuated by a spring, 47, which releases the pin when the projectile is discharged. The pin may be held in position in a similar manner to the pin, 33.

46 is the winding spindle of the motor, see Fig. 7.

The blower may consist of an involute casing, 36, and a fan runner or blades, 37, the intake, 38, being at the side, and the discharge, 39, at the periphery, see Fig. 7.

The gas passage, 8, opens at one end, at 15, through the nose of the projectile, and at the other end through a nozzle, 16, directed toward an igniter in a chamber, 18, open at 85 the side to the atmosphere, at 19, and to the air passage at 20. The gas passage, 8, also opens at the side, at 21.

The igniter may, for example, be a piece of platinum black or the like catalytic agent, 90 17, held down by clamps, 22, see Fig. 1; or a piece of pyrophorous metal, 48, and a friction wheel or striker, 49, on a spindle, 50, driven by a worm, 51, and worm wheel, 52, from the blower spindle, see Fig. 8; or an 95 electrically heated wire or a spark gap, 53, of a trembler coil, 54, connected to the battery, 12, by wires, 55, 56, see Fig. 9.

A non-return valve, 23, may be provided in the air passage, 7, to prevent downflow 100 of the air while traveling through the atmosphere, and of the gas in the airship.

The nose of the projectile may be fluted or equivalently formed, so that the ridges,

24, of the flutes facilitate cutting through wire or other obstructions, and the furrows, 25, of the flutes form passages for the gas and air to pass through to form the explosive mixture.

26 are wings or the like lateral projections, pivoted, at 27, in recesses, 28, at the sides of the projectile, to limit the penetration of the projectile into the gas bag of the airship. Their action is represented in Fig. 10. 1, where the dotted line, *x*, represents the outer envelop of the airship, and *y* represents the inner envelop or gas bag. The wings may be adjustable or set at different 15 distances along the projectile by being pivoted on slides, 29, in the recesses, 28, and secured by screws, 30, engaging holes, 31, or 32, see Fig. 6.

20 The operation of the projectile is as follows:—Upon being fired from a gun or other instrument, the blower is started, and the wings open, and upon striking the airship the projectile penetrates into the envelop, *x*, and *y*, and is arrested as shown. The air 25 blast from the blower then passes into the gas envelop, *y*, to form an explosive mixture with the hydrogen. Hydrogen also passes from the gas envelop, *y*, through the flute furrows, 25, and through the gas passages, 30, and 21, into the air envelop, *x*, to form an 35 explosive mixture with the air. When the explosive mixture reaches and passes through the nozzle, 16, into the chamber, 18, which has the air inlet, 20, and the vent, 19, the mixture is exploded by the igniter, 17, and fires back through the gas passages, 8, 21, and 15, so that explosions occur in both inner and outer envelops.

40 It will be obvious that for destroying a single chamber airship, the openings, 21, may be omitted or closed before the projectile is discharged.

45 In the case of a single envelop airship, a blower or its equivalent is necessary in the projectile to introduce a blast of air into the gas bag to produce an explosive mixture there.

50 What we claim as our invention and desire to secure by Letters Patent is:—

55 1. A projectile for destroying airships and the like comprising a shell having an air passage extending therethrough toward the nose end and a gas passage extending therethrough toward the tail end, a gas igniter in communication with the gas passage, openable stops at the exterior of the shell, and an air blower in communication with the air passage.

60 2. A projectile for destroying airships and the like comprising a shell having an air passage extending therethrough toward the nose end and a gas passage extending therethrough toward the tail end, a gas igniter in communication with the gas passage, openable stops at the exterior of the shell, and

means for forcing a blast of air along the air passage.

3. A projectile for destroying airships and the like comprising a shell having an air passage extending therethrough toward the 70 nose end and a gas passage extending therethrough toward the tail end, the gas passage being open at different distances between its ends, a gas igniter in communication with the gas passage, openable stops at the exterior of the shell, and means for forcing a blast of air along the air passage.

4. A projectile for destroying airships and the like comprising a shell having an air passage extending therethrough toward the 80 nose end and a gas passage extending therethrough toward the tail end, the passages being in communication, a gas igniter in communication with the gas passage, openable stops at the exterior of the shell, and 85 means for forcing a blast of air along the air passage.

5. A projectile for destroying airships and the like comprising a shell having an air passage extending therethrough toward the 90 nose end and a gas passage extending therethrough toward the tail end, a nozzle at the tail end of the gas passage, a chamber open to the atmosphere and to the air passage, a gas igniter in the chamber, the nozzle being 95 directed toward the gas igniting means, openable stops at the exterior of the shell, and means for forcing a blast of air along the air passage.

6. A projectile for destroying airships and the like comprising a shell having an air passage extending therethrough toward the nose end and a gas passage extending therethrough toward the tail end, a gas igniter in communication with the gas passage, adjustable stops at the exterior of the shell, and means for forcing a blast of air along the air passage.

7. A projectile for destroying airships and the like comprising a shell having an air passage extending therethrough toward the nose end and a gas passage extending therethrough toward the tail end, a catalytic gas igniter in communication with the gas passage, openable stops at the exterior of the shell, and means for forcing a blast of air along the air passage.

8. A projectile for destroying airships and the like comprising a shell having an air passage extending therethrough toward the nose end and a gas passage extending therethrough toward the tail end, a gas igniter in communication with the gas passage, openable stops at the exterior of the shell, means for forcing a blast of air along the air passage, and flutes on the nose of the projectile forming gas and air channels.

9. A projectile for destroying airships and the like comprising a shell having an air passage extending therethrough toward the 130

nose end and a gas passage extending therethrough toward the tail end, a gas igniter in communication with the gas passage, openable stops at the exterior of the shell, means 5 for forcing a blast of air along the air passage, and a non-return valve in the air passage.

10. A projectile for destroying airships and the like comprising a shell having an air 10 passage extending therethrough toward the nose end and a gas passage extending therethrough toward the tail end, a gas igniter in communication with the gas passage, openable stops at the exterior of the shell, an air 15 blower in communication with the air passage, means for driving the blower, and means for controlling the driving means.

11. A projectile for destroying airships and the like comprising a shell having an 20 air passage extending therethrough toward the nose end and a gas passage extending therethrough toward the tail end, a gas igniter in communication with the gas passage, openable stops at the exterior of the 25 shell, an air blower in communication with the air passage, means for driving the blower, means projecting through the walls

of the shell for controlling the driving means, and resilient means for releasing the controlling means.

12. A projectile for destroying airships and the like comprising a shell having an air 30 passage extending therethrough toward the nose end and a gas passage extending therethrough toward the tail end, a gas igniter 35 in communication with the tail end of the gas passage, openable stops at the exterior of the shell, an air blower in communication with the tail end of the air passage, mechanical means for driving the blower, and 40 means projecting through the walls of the shell for controlling the driving means, said controlling means releasing the driving means when not held in engagement therewith.

45 In witness whereof we affix our signatures, in presence of two subscribing witnesses.
